CLAIM

We claim the ornamental design for a tank, as shown and described.

DESCRIPTION

FIG. 1 is a front elevational view of our tank showing our new design;

FIG. 2 a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view thereof;

FIG. 8 is an enlarged view of the encircled portion in FIG. 7;

FIG. 9 is an enlarged view of the encircled portion in FIG. 7;

FIG. 10 is a rear perspective view thereof;

FIG. 11 is an enlarged view of the encircled portion in FIG. 10; and,

FIG. 12 is an enlarged view of the encircled portion in FIG. 10.

(Continued)

The dashed lines in the figures illustrate portions of the tank that form no part of the claimed design.
